Primary Examiner — Nathan M Johnston(74) *Attorney, Agent, or Firm* — Morse, Barnes-Brown & Pendleton, P.C.; Sean D. Detweiler, Esq.(57) **CLAIM**

The ornamental design for a personal ambient air temperature modification device lid, as shown and described.

DESCRIPTION

FIG. 1 is a front view of a personal ambient air temperature modification device lid;

FIG. 2 is a left side view thereof;

FIG. 3 is a rear view thereof;

FIG. 4 is a right side view thereof;

FIG. 5 is a top plan view thereof;

FIG. 6 is a bottom plan view thereof;

FIG. 7 is a front isometric view thereof; and,

FIG. 8 is a front isometric view of the personal ambient air temperature modification lid with the removable handle separated for ease of illustration.

The broken lines show portions of the design that form no part of the claimed design.
